UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

DIFFERENTIAL FEEDING MECHANISM.

1,313,524.

Specification of Letters Patent.

Patented Aug. 19, 1919.

Application filed June 10, 1916. Serial No. 102,851.

To all whom it may concern:

Be it known that I, ALBERT H. DE VOE, a citizen of the United States, residing at Westfield, in the county of Union and State of New Jersey, have invented certain new and useful Improvements in Differential Feeding Mechanisms, of which the following is a specification, reference being had therein to the accompanying drawings.

This invention relates to that class of differential feeding mechanism for sewing machines in which two differentially actuated feed-dogs are given synchronous feed-and return-movements of substantially equal amplitude, the rising-and-falling movements being so timed that one of the feed-dogs is maintained elevated above the surface of the work-plate for a longer period of time during its feeding stroke than the other feed-dog.

One of the objects of the invention is to provide a simple, durable and effective differential feeding-mechanism particularly for that class of sewing machines having a rotary shaft below the work-plate although adapted for machines of other types. Another object of the invention is to provide a manual control for readily changing the feeding action of the improved mechanism without stopping the machine. Other objects will appear from the following description and claims.

According to the present improvement in its preferred embodiment, two feed-levers or bars, extending in the same general direction and each carrying a feed-dog, are pivoted at one end to a rocking frame to which feed-and return-movements are imparted through a sliding pin-and-socket connection with a strap embracing an adjustable eccentric mounted on the looper actuating shaft. Rising-and-falling movements are given to the primary feed-lever through another pin-and-socket connection with a strap embracing another eccentric on the looper-shaft. Rising-and-falling movements are imparted to the secondary feed-lever from the primary lever through an intermediate rocking element or differentiator pivoted to the primary feed-lever and connected to the frame through a link. An adjustable pin, carried by and movable lengthwise of the secondary lever, enters a slot in the differentiator which acts to raise and lower the secondary lever relative to the primary lever and differen-

tiate the rising-and-falling movements of said levers during the feeding movement. A manually controlled lever is provided to shift the adjustable pin lengthwise of the secondary lever to vary the effective action of the differentiator.

In the accompanying drawings, which form a part of this specification, Figure 1 is a side elevation of the feeding-mechanism showing portions of the frame in section. Fig. 2 is a reverse side elevation of the mechanism shown in Fig. 1 at the same period in the cycle of feeding movements. Fig. 3 is a plan view. Fig. 4 is a rear elevation of the feeding-mechanism. Figs. 5 and 6 illustrate different relative positions assumed by the elements of the feeding-mechanism during a cycle of operations. Fig. 7 shows the supporting and actuating pin for the secondary lever in one of its extreme positions of adjustment. Fig. 8 is a plan view of the secondary feed-lever. Fig. 9 is a plan view of the primary feed-lever, and Fig. 10 is a section on the line 10—10, Fig. 1.

The present improvement is a development of the feeding-mechanism disclosed in my copending application Serial No. 85,535, filed May 21, 1916, and in its preferred embodiment is shown applied to a flat-bed machine having a base 1 and an elevated cloth-plate *p* between which and the base is journaled the looper actuating shaft 3 having the reduced forward end-portion 4. The primary feed-dog 5, which in the present embodiment may also be termed the auxiliary or fulling feed-dog, is provided with a downwardly extended shank 6 having a slot 6' entered by a screw 6'' adapted to hold the shank 6 in adjusted position in a seat provided therefor in the head 7 of a slotted cross-bar 8 secured by the screw 9 to the seat 10 formed in the upper front end portion of the primary feed-lever 11, the rearward end of which is extended laterally, as shown in Fig. 9, and provided with spaced tubular bosses 12, 12 which are freely entered by the pin 13 journaled in spaced tubular bosses 14, 14 projecting upwardly from the H-shaped rocking frame 15 having lower spaced tubular bosses 16, 16, within which is fixedly secured the shaft 17, journaled in bushings 18, 18 fitted within suitable apertures provided therefor in the frame.

The primary feed-lever 11 has depending

therefrom a tubular boss 19 affording a socket in which is slidably fitted a pin 20 projecting laterally from a strap 21 embracing the feed-lifting eccentric 22 fixed upon 5 the reduced portion 4 of the shaft 3.

The rocking frame 15 is provided with the lateral arm 23 formed at its end with the tubular boss 24 within which is fixedly secured the eccentric shank 25, Fig. 2, of a 10 pin 25 which freely enters a socket afforded by a tubular boss 26 formed on the eccentric strap 27 which embraces the feed-actuating eccentric 28 adjustably mounted, in a manner well-known, on the shaft 3.

15 The secondary feed-dog 29, which in the present instance is the main feed-dog, has a shank 30 seated in the enlarged free end of the secondary feed-lever 31 extending alongside the primary feed-lever 11 and 20 having near its rearward end a transverse tubular boss 32 fixedly secured to the pin 13 in a position intermediate the spaced bosses 12 on the primary feed-lever.

25 The rising-and-falling movements imparted to the primary feed-lever are transmitted to the secondary feed-lever, and the feed- and return-movements of the primary lever are utilized to differentiate the rising-and-falling movements of the secondary 30 feed-lever relative to the primary feed-lever, through the following connections: Journaled in a tubular boss 33 formed transversely and intermediate the ends of the primary feed-lever 11, is the pivot-pin 34 35 extending laterally from one side face of a rocking differentiator 35 formed with a depending arm 36 connected by a screw-pin to one end of a link 37 whose opposite end is pivotally connected to the top of a post 38 40 fixed to the base 1. The differentiator 35 is formed with a substantially horizontally extending slot 39, shown in the cross-section in Fig. 10, in which is slidably fitted the rectangular block 40 loosely mounted on the 45 pin 41 projecting, through a slot 42 in the secondary feed-lever, from a slide-plate 43 let into a longitudinally extending recess 44 in the outer side face of the secondary feed-lever and suitably held in position in said 50 recess by a screw 45 which extends through a slot 46 in the slide-plate and is threaded into the secondary feed-lever.

55 Provision is made for adjusting the slide-plate 43 longitudinally of the recess 44 without stopping the machine. The screw 47 carried by the slide-plate 43 is embraced by the forked extremity of a bellcrank-lever 48 pivoted to the secondary feed-lever by a screw-pin 49. The other arm of the bellcrank-lever 48 which is formed as a handle 50 supports a screw 50' positioned in the slot 51 formed in the downwardly extended rear end of the secondary feed-lever 31 and adapted to hold the bellcrank-lever in adjusted position if tightened.

It is not necessary, however, to fix the bellcrank-lever in position by use of the screw 50' as said lever may be manually controlled during the sewing operation either by hand or through the usual treadle or knee-shift 70 connection 52. When using the connection 52 it is desirable to provide a spring 53 to raise the free end of the bellcrank-lever, as will be obvious to those skilled in the art.

The connections between the differentiator 75 35 and the primary and secondary feed-levers are so proportioned that when the bellcrank-lever is at one extremity of its movement the pin 41 and pivot-pin 34 are in axial alinement. In this position of the 80 parts the differentiator 35 is ineffective and the primary and secondary feed-levers move together as one.

I prefer to employ a presser-foot having independently movable sole portions 54 and 85 55. The forwardly disposed sole portion 54 is pivotally connected at 56 to a bar 57 pivoted at 58 to the rearwardly disposed sole portion 55. A spring 59 serves to yieldingly depress the bar 57 carrying the sole 90 portion 54. The rearwardly disposed sole portion 55 is carried by the usual spring-pressed presser-bar 66.

In the operation of the mechanism, with the parts in the position shown in Figs. 1 95 and 2, as the shaft 3 turns in the direction of the arrow, the feed-dogs begin to rise from their lowest positions. At the same time the eccentric 28 rocks the frame 15 to the left in Fig. 2, which imparts return 100 movements to the feed-dogs. At this time the primary feed-dog 5 extends slightly higher than the feed-dog 29 but as said levers are moved toward the position shown in Fig. 5, the differentiator 35 is tilted and 105 acts as a lever to lift the pin 41 sufficiently to raise the feed-dog 29 substantially to the level of the feed-dog 5, in which relative positions the feed-dogs are lifted above the surface of the work-plate *p* by the action of 110 the lifting eccentric 22 and moved to the position shown in Fig. 5.

As the feed-dogs are moved in the direction of feed, from the position shown in Fig. 5 to that shown in Fig. 6, the differentiator 35 is tilted rearwardly and acts to lower the pin 41 relative to the pin 34 thus lowering the feed-dog 29 below the surface of the work-support *p* before the feed-dog 5 has finished its feeding stroke. As a result of this action the rearward sole portion 55 will hold the portion of the work advanced by the feed-dog 29 against the throat-plate *p* while the forward feed-dog 5, in finishing its feeding stroke, will crowd 125 or full in the material to a certain extent. The relative positions occupied by the feed-dogs 5 and 29, one forwardly of the other, may obviously be reversed, thereby producing a stretching feed.

While I have shown and described the preferred embodiment of the invention, I realize that it is susceptible of considerable modification in the construction and arrangement of the various parts, within the scope of the invention.

Having thus set forth the nature of the invention, what I claim herein is:—

1. Differential feeding mechanism for 10 sewing machines comprising, in combination, primary and secondary feed-dogs, primary and secondary levers supporting said feed-dogs, respectively, a pivotal connection between said levers, means independent of 15 said pivotal connection whereby endwise movements derived from one of said levers are converted into differential rising-and-falling movements of the other lever, and manually controlled means for varying the 20 action of said first mentioned means while the machine is in operation.

2. Differential feeding mechanism for 25 sewing machines comprising, in combination, a main-shaft, primary and secondary feed-dogs, pivotally connected primary and secondary levers supporting said feed-dogs, respectively, means connected to the main-shaft for imparting rising-and-falling and 30 endwise feeding movements to said levers, means independent of said pivotal connection whereby endwise movements of said primary lever are utilized to differentiate the rising-and-falling movements of one of 35 said levers relative to the other, and manually controlled means for varying the action of said last-mentioned means while the machine is in operation.

3. Differential feeding mechanism for 40 sewing machines comprising, in combination, a rocking and endwise movable primary lever carrying a feed-dog, actuating means therefor, a secondary lever pivoted to said primary lever and carrying another feed-dog, adjustable means comprising a 45 differentiator carried by said primary lever for imparting differential tilting movements to said secondary lever relative to said primary lever, whereby differential feeding actions are imparted to said dogs, and a 50 manually controlled device for adjusting said adjustable means without stopping the machine.

4. Differential feeding mechanism for 55 sewing machines comprising, in combination, a rocking and endwise movable primary lever carrying a feed-dog, actuating means therefor, a secondary lever connected to said primary lever and carrying another feed-dog, adjustable means comprising an 60 element carried by said primary lever and anchored to the frame for imparting differential rocking movements to said secondary lever relative to said primary lever, whereby differential feeding actions are imparted to said feed-dogs, and a manually controlled

device for adjusting said adjustable means without stopping the machine.

5. Differential feeding mechanism for 70 sewing machines comprising, in combination, primary and secondary levers, feed-dogs carried thereby, means for imparting endwise feeding movements of equal amplitude to said levers, means for imparting rising-and-falling movements to said levers including adjustable differentiating means 75 for transmitting the rising-and-falling movements of one lever to the other, and manually controlled means for adjusting said adjustable means without stopping the machine.

6. Differential feeding mechanism for 80 sewing machines comprising, in combination, a frame, primary and secondary levers, feed-dogs actuated thereby, a movable supporting element to which said levers are pivotally connected, a differentiator pivotally connected to one of said levers and anchored to the frame, an adjustable connection between said differentiator and the other of 85 said levers and manually controlled means for adjusting said connection without stopping the machine.

7. Differential feeding mechanism for 90 sewing machines comprising, in combination, pivotally mounted primary and secondary feed-levers, means for imparting rising-and-falling and simultaneous feed-and return-movements to said levers, means carried by said feed-levers for differentiating the rising-and-falling movements thereof, and a manually controlled lever pivotally mounted on one of said feed-levers for varying the action of said differentiating means.

8. Differential feeding mechanism for 100 sewing machines comprising, in combination, a main frame, a rocking frame pivoted to said main frame, primary and secondary levers pivoted to said rocking frame and each carrying a feed-dog, means for imparting rising-and-falling movements to said 110 primary lever, a slotted differentiator pivotally mounted on said primary lever, a link connection between said differentiator and said main-frame, and a pin adjustably mounted on said secondary lever and entering the slot in said differentiator.

9. Differential feeding mechanism for 120 sewing machines comprising, in combination, a main frame, a rocking frame pivoted to said main frame, primary and secondary levers pivoted to said rocking frame and each carrying a feed-dog, means for imparting rising-and-falling movements to said primary lever, a slotted differentiator pivotally mounted on said primary lever, a link 125 connection between said differentiator and said main frame, a pin adjustably mounted on said secondary lever and entering the slot in said differentiator, and a manually controlled device carried by said secondary 130

lever and adapted to permit adjustments of said pin without stopping the machine.

10. Differential feeding mechanism for sewing machines comprising; a rocking and endwise movable primary lever, a first feed-dog carried thereby, a secondary lever, a second feed-dog mounted thereon, adjustable means including a differentiator carried by said primary lever for imparting differ-

ential feed movements to said secondary lever relatively to said primary lever, and a treadle-controlled device for effecting the desired adjustment of the feed differentiating means.

In testimony whereof, I have signed my name to this specification.

ALBERT H. DE VOE.
